HANDLEBAR FOR BICYCLES

Albert J. Fritz, Wilmette, Ill., assignor to Schwinn Bicycle Company, a corporation of Illinois

Filed Nov. 10, 1966, Ser. No. 4,621

Term of patent 14 years

(Cl. D90—11)

FIG. 2 is a perspective view from one side of the handlebar;

FIG. 3 is a top plan view;

FIG. 4 is a front elevational view; and

FIG. 5 is a rear elevational view.

The elements shown in broken lines in FIG. 1 are included for illustrative purposes only.

I claim:

The ornamental design for a handlebar for bicycles, as shown and described.
